CLAIM

The ornamental design of a display screen for medical imaging apparatus with touch graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of the display screen for medical imaging apparatus with touch graphical user interface;

FIG. 2 is a perspective view thereof; and,

FIG. 3 is an enlarged front elevation view shown without the display screen for medical imaging apparatus.

In FIGS. 1 and 2, the broken lines are for the purpose of illustrating a display screen for medical imaging apparatus with touch graphical user interface and form no part of the claimed design.
